DESIGN FOR A HAT FORM

Harry E. Rich and Joseph Greenberg, New York, N. Y.

Application November 11, 1936, Serial No. 65,849

Term of patent 3½ years

To all whom it may concern:

Be it known that we, Harry E. Rich, and Joseph Greenberg, both citizens of the United States and both residents of New York city, in the county of New York and State of New York, have invented a new, original, and ornamental Design for a Hat Form, of which the following is a full, clear and exact description: reference being had to the accompanying drawing, forming a part thereof:

Fig. 1 is a perspective view of a hat form adapted to be used in forming a draped hat, and showing our new design.

Fig. 2 is a rear elevational view of Fig. 1.

The dominant feature of the design is the representation of eyes and a nose at the lower front portion of the hat form as shown.

We claim:—

The ornamental design for a hat form as shown and described.

HARRY E. RICH.
JOSEPH GREENBERG.
